To all whom it may concern:

Be it known that I, SWITS CONDÉ, of Oswego, in the county of Oswego, in the State of New York, have invented new and useful Improvements in Design for Knitted Overshirts, of which the following, taken in connection with the accompanying drawing, is a full, clear, and exact description.

The annexed drawing represents a knit overshirt folded in the usual manner, to expose the front and collar thereof.

My design consists, essentially, in the front A and collar C, being of a different pattern than the body B. The front A, I further ornament 15 by a sham lacing, a, running down the center thereof, as shown.

What I claim is—

In testimony whereof I have hereunto signed my name and affixed my seal, in the presence of two attesting witnesses, at Oswego, in the county of Oswego, in the State of New York, 25 this 15th day of May, 1883.
